UNITED STATES PATENT OFFICE.

FRANK P. VAVRA, OF CICERO, ILLINOIS.

PARAFFIN-COATING MACHINE.

1,345,720.

Specification of Letters Patent.

Patented July 6, 1920.

Application filed October 16, 1918. Serial No. 253,399.

To all whom it may concern:

Be it known that I, FRANK P. VAVRA, a citizen of the United States, and resident of Cicero, in the county of Cook and State of Illinois, have invented certain new and useful Improvements in Paraffin-Coating Machines, of which the following is a full, clear, and exact specification.

My invention is concerned with paraffin coating machines of the general class shown in the Vavra Patent 1,198,976, and is designed to produce such a machine as will have a very short path for the carton or other blank through the bath of melted paraffin so that while the blank is thoroughly coated, the paraffin will not have time to penetrate the body of the blank during its passage through the bath.

To this end it consists primarily in a tank for the melted paraffin with a main gaging roll slightly immersed in the bath and cooperating with two smaller rolls entirely or substantially immersed in the bath, the first of the smaller rolls acting primarily as a feed roll, while the second one has the main function of acting as a final gaging roll and determining the thickness of the coating of paraffin upon the blank as it emerges from between the main roll and the said second smaller roll.

Associated with the gaging rolls, I may employ a special pair of feeding rolls associated with the proper guide fingers designed to carry the coated blanks up over the edge of the paraffin tank and down into the receiving angle of the blank conveying cords located in the adjacent end of the cooling water tank.

It is further concerned with a novel arrangement of blank carrying mechanism so that the blank will be fed squarely into the receiving angle of the final pair of rolls from which the blanks emerge from the machine.

To illustrate my invention, I annex hereto four sheets of drawings in which the same reference characters are used to designate identical parts in all the figures of which—

Figure 1 is a side elevation, partly in section on the line 1—1 of Fig. 3;

Fig. 2 is a vertical section on the line 2—2 of Fig. 3;

Fig. 3 is a top plan view;

Fig. 4 is a side elevation of the complete machine, but on a much smaller scale and 55 with the cooling water tank shown in longitudinal section;

Fig. 5 is an end elevation of a portion of the end of the machine containing the cooling water tank; and 60

Fig. 6 is a side elevation of one of the pair of bars used to space the cords in the cooling water tank.

As best seen in Fig. 4, I employ a pair of side frames 10, which are connected at their 65 ends by the crossbars 11 to form a rigid rectangular frame. In this frame, in any suitable manner I support a pair of tanks, the tank 12 at the receiving end, being adapted to contain melted paraffin, while the larger 70 tank 13 is adapted to contain cold water for hardening the paraffin on the blanks as they are discharged thereinto after being coated by the apparatus associated with the tank 12.

Power will be applied to the machine in 75 any suitable manner as by belt to the belt wheel 14 seen in Fig. 4 secured on the end of the drive shaft 15, which is journaled in suitable bearings 16 secured on the side frames 10. The shaft 15 has secured thereon the miter gear 17 meshing with the miter gear 18 secured on the adjacent end of the shaft 19, shown in Figs. 4 and 5, which is journaled in the bearing 20 supported from the bracket 21 at one end and at the other 80 end in the bearing 21 supported from the side frame 10 at that end of the machine.

The paraffin tank 12, as best seen in Fig. 2, is in the form of a jacketed tank open at the top and provided with a steam pipe 22 90 by which steam may be applied to the jacket to keep the paraffin therein at the proper temperature. An overflow pipe 23 extending through the bottom of the tank serves to keep the paraffin at the desired level. Within the paraffin tank and adjacent the ends thereof are a pair of bearing side frames 24 and 25, which are symmetrical, and are supported on the driving shaft 15 which passes through suitable apertures therein, and which are also supported by the set-screws 26 threaded through projections 27 on the outside of the bearing side frames and engaging the tops of the side frames 10, as

clearly shown in Fig. 1. These bearing side frames are secured together and spaced apart by the flat bar 28 at one end, said bar being screwed thereto, as seen in Fig. 3, and 5 by the angle bar 29, likewise secured at its ends to said bearing side frames and serving as a guide, as will be subsequently described. The side frames are also connected by another guide bar 30.

10 The blanks to be coated may be conveniently supported on a holder 31, secured on the extensions 32 of the bearing side frame castings 24 and 25. Journaled adjacent the end of the support 31 is a feed roller 15 33 preferably having its periphery with annular corrugations therein and secured upon the shaft 34 journaled in the frames 24 and 25. Above the feed roller 33 is a plurality of feed disks 35 secured on the shaft 36 likewise 20 journaled in the frames 24 and 25. The drive shaft 15 has secured thereon just within the bearing side frame 24 a spur-gear wheel 38 secured on the shaft 36 and in turn meshing with another spur-gear 25 wheel 39 secured on the shaft 34, so that the feed rolls 33 and 35 are driven by the shaft 15.

Journaled in the carrying side frames 24 and 25 is a shaft 40 upon which is secured 30 the main or large gaging roll 41, which is preferably a hollow metallic roll having a covering of felt or some similar fibrous material and driven by reason of the spur-gear wheel 42 secured on the shaft 40 and meshing 35 with the spur-gear wheel 37. Likewise journaled in the side bearing frames 24 and 25 is a shaft 43 having secured thereon the feed roll 44, preferably constructed like the gaging roll 41 and having its felt covered 40 surface engaging the similar surface of the roller 41 so that cartons will be gripped between the two rollers and fed between them, they being rotated at the same peripheral velocity by reason of the spur-gear 45 wheel 45 secured on the shaft 43 meshing with the spur-gear wheel 42. The blanks to be coated are fed down into the paraffin and between the rolls 41 and 44 by the action of the feed rolls 33 and 35, the blanks being 50 guided over the inclined surface of the angular bar 29 and beneath the wire guides 46 hooked around the shaft 36 and having the curved ends coöperating with the rod 47 connecting the bearing side frames 24 and 25.

The bearing side frames 24 and 25 have formed therein a pair of slots 48 of the proper width to accommodate the vertical movement therein of the shaft 49 which has 60 secured thereon the smaller gaging roll 50 which is of the same construction as the larger gaging roll 41. The shaft 49 is journaled in a pair of eye bearings 51 formed on the lower end of the rods 52 which extend 65 upward through elongated passages

formed in the lugs 53 projecting outward from the bearing side frames 24 and 25. Nuts 54 are threaded on the upper ends of the rods 52 and helically coiled expanding springs 55 surrounding the rods between the nuts 54 and the top of the lugs 53 serve to pull the gaging roll 50 against the gaging roll 41 by a pressure that is regulated by adjusting the nuts 54. The gaging roll 50 is substantially immersed in the paraffin, and is rotated at the same peripheral velocity as the companion roll 41 by reason of the spur-gear wheel 56 secured on the shaft 49 meshing with the spur-gear wheel 42. The speed of rotation of these 70 gaging rolls is sufficient so that the paraffin cannot flow down into the diverging angle between said rollers when they are running, and as a consequence the thickness of the coat of paraffin is determined by the 75 covering of the rolls 41 and 50 and the pressure between them.

The coated blanks thus emerging from between the gaging rolls 41 and 50 are preferably directed to a pair of feed rolls 57 and 58 by a plurality of guide wires 59 hooked over the rod 60 extending between the side frames 10 and the rod 61 secured in the bearing side frames 24 and 25, and co-operating with the guide members 62 sprung 80 on the bar 28. These guide members are preferably formed of sheet metal having a pair of apertures 63 cut therein to accommodate the bar 28 and bent into the generally U-shape in vertical cross-section, the 85 guiding edges 64 being curved, as shown in Fig. 2, to direct the blank from the gaging rolls 41 and 50 to the feeding rolls 57 and 48. These guide members 62 are held in any desired adjustment by the leaf springs 65 90 interposed between the adjacent ends of the slots 63 and the bar 28, they being secured from movement by the screws 66 threaded through the tongue 67 and engaging the adjacent surface of the bar 28.

The feed rolls 57 and 58 are preferably formed by hollow metal and have a coating of felt so as not to mar the coated surface of the cartons. As it is desirable to keep the paraffin on the blanks warm and semi-liquid until the blanks are plunged into the cooling water, I make these rolls 57 and 58 hollow and open into one end thereof the steam pipes 68 and 69 which serve to supply steam to the interior of the rolls and to 105 drain off the water of condensation. The rolls 57 and 58 are journaled in suitable bearings in the bearing side frames 24 and 25 and are provided with spur-gear wheels 70 and 71 meshing with each other and 110 driven by the spur-gear wheel 72 journaled on a stud 73 projecting from the side frame 24 and meshing with the spur-gear wheel 56. All the various spur-gear wheels in the trains have substantially the same pitch diameter 115 120 125 130

as their associated rolls so that all the rolls throughout the apparatus are operated at the same peripheral velocity as is necessary to feed the blanks through the machine at the proper uniform speed.

Referring now more especially to Figs. 2 and 4, a tank 13 has mounted therein a pair of rolls 73 and 74 journaled in a pair of brackets 75 supported from the side frames 10. There are three other rolls 76, 77 and 78 located in the position shown and journaled in the brackets 79, 80 and 81 similarly secured from the side frames 10 and extending down into the water in the tank 13. At the discharge end of the tank 13 is a pair of bearing brackets 82 and 83 secured upon the side frames 10 and having journaled therein a pair of feed rollers 85 and 86 geared together at one end by the spur-gears 87 and 88. An idle feed roller 89 is also journaled in the frames 82 and 83. The shaft of the roller 86 has on its other end the spur-gear pinion 90 meshing with an intermediate pinion 91 journaled 25 on a stud shaft projecting from the bearing frame 83 and meshing with a spur-gear wheel 92 secured on the end of the shaft for the roller 93, which roller together with the companion roll 94, is journaled in suitable bearings in the frame pieces 82 and 83 so that their meeting surfaces, which are preferably coated with rubber, may be pressed into contact by the set-screws 95. The shaft 19 has secured on its adjacent end 35 the miter gear 96 which meshes with miter gear 97 secured on the shaft of the roll 93, so that as the machine is operated, the rollers 85 and 86, 89 and 93 and 94 will be rotated at the same peripheral velocity. 40 Running over the rolls 73, 77, 86, 89, 78 and 76 are a set of strings or bands 98 and extending over the rolls 85, 78, 76 and 74 are a similar set of strings or bands 99, which two sets of strings 98 and 99 are parallel and close to each other on their adjacent runs so that blanks fed into the receiving angle between the rolls 73 and 75 will be carried down through the carrying way and up over the roll 89 which dis- 45 charges them substantially horizontally between the rolls 85 and 86, which in turn deliver them to the drying rolls 93 and 94 which squeeze off the moisture adhering to the paraffin on the blanks. To keep the strings 98 and 99 properly spaced apart I employ a pair of rods 100 and 101 extending across the tank and supported by the brackets 102 secured to the side frames 10. These rods 100 and 101 have a series of pins 50 103 projecting upwardly therefrom and serving to guide the strings 98 and 99 which will be spaced apart to such an extent as is desirable for the particular width of length being coated.

60 The roll 94 is also provided with a spur-

gear wheel 104, meshing with the spur-gear wheel 92 so as to cause the rolls 93 and 94 to rotate in unison.

The operation of the complete apparatus will be readily apparent to those skilled in the art, and it will be seen that the blanks entering the machine between the feed rolls 33 and 35 will be guided down into the melted paraffin between the rolls 41 and 44, and thence pass over the top of the 75 guide member 30 between the rolls 41 and 50, which latter rolls gage the amount of paraffin applied and allowed to remain on the surfaces of the cartons or blanks. Emerging from between the rolls 41 and 50 the blanks are forced up against the curved guide surfaces 64 of the guide member 62 and between the feed rolls 57 and 58, which keep the paraffined surfaces of the blank heated and soft until the blanks are 85 plunged into the cold water in the tank 13 through which the blanks are passed in the customary manner and are finally discharged from the rolls 93 and 94.

While I have shown and described my invention as embodied in the form which I at present consider best adapted to carry out its purposes, it will be understood that it is capable of modifications and that I do not desire to be limited in the interpretation of the following claims except as may be necessitated by the state of the prior art.

What I claim as new and desire to secure by Letters Patent of the United States is:

1. In an apparatus of the class described, 100 the combination with a tank, of a gaging roll journaled thereover and dipping into the bath, a feed roll located in the tank beneath the front side of the gaging roll and co-operating therewith, a second gaging roll 105 located in the tank beneath the rear side of the main gaging roll and spring pressed into engagement therewith, and gearing for said rolls to drive them with the same peripheral velocity.

2. In an apparatus of the class described, 110 the combination with a tank, of a gaging roll journaled thereover and dipping into the bath, a feed roll located in the tank beneath the front side of the gaging roll and co-operating therewith, a second gaging roll 115 located in the tank beneath the rear side of the main gaging roll and spring pressed into engagement therewith, a pair of feed rolls located over the edge of the tank, 120 guides to direct the blanks from the pair of gaging rolls to the feed rolls, and gearing for said rolls to drive them with the same peripheral velocity.

3. In an apparatus of the class described, 125 the combination with a tank, of a gaging roll journaled thereover and dipping into the bath, a feed roll located in the tank beneath the front side of the gaging roll and co-operating therewith, a second gaging 130

roll located in the tank beneath the rear side of the main gaging roll and spring pressed into engagement therewith, guide members to direct the blanks from the feed roll to the receiving angle of the gaging rolls, and gearing for said rolls to drive them with the same peripheral velocity.

4. In an apparatus of the class described, the combination with a main frame, of a 10 paraffin tank supported therein, a driving shaft journaled in said main frame, a supporting bar parallel to the driving shaft, a pair of bearing side frames to the top of which the supporting bar is secured near 15 the ends of the paraffin tank and supported by the driving shaft and the main frame, a plurality of feeding and gaging rolls journaled in the bearing side frames and extending into the paraffin tank, and gearing connecting said rolls and the driving shaft.

5. In a device of the class described, the combination with a paraffin tank, of a pair of feed rolls journaled above the level of the 25 paraffin but discharging downwardly therewith, a large gaging roll dipping into the paraffin, a feed and gaging roll co-operating with the large gaging roll to grip blanks coming from the pair of feed rolls, 30 a smaller gaging roll co-operating with the large roll, and gearing to drive the rolls at the same peripheral velocity.

6. In a device of the class described, the combination with a paraffin tank, of a pair 35 of feed rolls journaled above the level of the paraffin but discharging downwardly therewith, a large gaging roll dipping into the paraffin, a feed and gaging roll co-operating with the large gaging roll to grip blanks 40 coming from the pair of feed rolls, a smaller gaging roll co-operating with the large roll, a guide member adjacent the large gaging roll between the feed engaging roll and the smaller gaging roll, and gearing to drive 45 the rolls at the same peripheral velocity.

7. In a device of the class described, the combination with gaging rolls adapted to supply paraffin to the blanks, of a cold water tank, a pair of soft surfaced, inter-

nally heated feed rolls located between the 50 gaging rolls and the cold water tank, adapted to deliver the coated engaged blanks, while still hot from the gaging rolls into the cold water tank, and gearing to 55 rotate the rolls at the same peripheral velocity.

8. In an apparatus of the class described, the combination with a plurality of feeding and gaging rolls and means for supplying the latter with melted paraffin, of 60 guiding mechanism associated therewith consisting of a bar, with a plurality of guide members, U-shaped in cross-section strung along on the bar, springs interposed between the guide members and the bar, 65 and screws threaded through the guide members and engaging the bar to secure the guide members in any desired position.

9. In an apparatus of the class described, the combination with a bearing frame, of 70 a gaging roller journaled in stationary bearings in said frame, said frame containing a pair of slots for a gaging roll shaft extending therethrough, guide apertures in lugs carried by the frame in alignment with 75 the slots, a pair of rods extending through the guide apertures and having eye bearings, springs surrounding the rods, and a gaging roller journaled in the eye bearings.

10. In an apparatus of the class de- 80 scribed, the combination with a cold water tank, of a pair of feeding rolls journaled at the rear of and above said tank, plural rollers journaled in the tank below the water level, strings running over said rollers to feed blanks through the water, and a feeding roll over which the strings run 85 journaled in advance of and at the level of the lower one of the first mentioned pair of feed rolls.

In witness whereof I have hereunto set my hand and affixed my seal this 24th day of September, A. D. 1918.

FRANK P. VAVRA.
